COMBUSTION CONTROL

Wayland R. Miller, Whitefish Bay, Wis., assignor
to Perfex Corporation, Milwaukee, Wis., a cor-
poration of Wisconsin

Application May 1, 1941, Serial No. 391,280

30 Claims. (Cl. 236—9)

This invention relates in general to automatic combustion control and is more particularly concerned with control of stoker fired furnaces.

In order to increase the efficiency of a furnace fired by fuel burners or stokers it has been usual practice to utilize an automatic draft regulator which acts to maintain a predetermined draft in the furnace when the burner or stoker is in operation. In large installations these draft regulators usually consist of a damper located in a flue and positioned by a reversible motor which is controlled by a draft responsive control. In smaller installations, the draft regulator consists of a self-contained or "barometric" damper. This type of damper usually is formed of a substantially balanced damper blade responsive to the draft and controlling the admission of basement air into the flue. In systems in which the burner or stoker is operated by "on-off" type of controls, these automatic draft controls have sometimes been provided with supplemental control means for causing the draft control to assume a position of minimum draft during the "off" periods, this serving to minimize cooling of the furnace by air flow therethrough.

It is an object of the present invention to provide an improved furnace draft control system of the type described in which the draft control upon stopping of the burner or stoker is first moved to a position of maximum draft and maintained in this position for a period of time and then moved toward a position of minimum draft. In stoker fired systems this novel control means and sequence of control serves to minimize smoking and to prevent any discharge of smoke into the furnace room when the stoker is shut down. In devices of this character, green coal is constantly fed to a retort in which it is burned under forced draft. While the stoker is in operation, the air being forced thereto causes good combustion of this green coal and thus only an insignificant amount of smoke is emitted from the fire. However, when the stoker is shut down the forced draft is discontinued, with the result that incomplete combustion of the green coal occurs, thus causing considerable smoke to emit from the stack. By the arrangement of the present invention, a maximum natural draft is provided for a period of time after the stoker shuts down which causes a substantial flow of air through the coal bed, thus rendering better combustion of the green coal in the retort and minimizing smoking. This positioning of the damper for obtaining maximum natural draft for a period of time also insures that all of the smoke emitted from the

fire will pass through the stack, thus avoiding any discharge of smoke into the furnace room when the stoker is shut down. In fluid fuel burning installations the control sequence of the present invention has the advantage of providing a purging period after each burner operation to insure removal of any unburned fuel before the burner is restarted.

In stoker installations and also in some types of fluid fuel burning installations, air supply control dampers are used which function to control the supply of air during the "on" periods and to prevent the supply of air during the "off" periods. It is a further object of this invention to provide a control system in which control means for the draft control damper and the air supply control are interlocked or correlated in a manner to maintain the air damper open and the draft damper in a position of maximum draft for a period of time after the combustion means is shut down. This type of control of the air damper and the draft damper insures a good natural draft through the furnace for a period of time after the shutdown occurs, thereby reducing smoking to a minimum or providing a positive purging operation.

It is a further object of this invention to provide a control system for the air supply and the draft damper of a stoker fired system which acts after starting of the stoker to cause relatively quick movement of the damper to a position providing a substantial draft, while delaying the initiation of a substantial air supply. This novel sequence of control has the advantage of reducing fly ash to a minimum when the stoker first starts, and at the same time insuring that all products of combustion are carried from the furnace into the stack so as to avoid smoking up the furnace room.

Another object of the invention is the provision of a draft damper control having a thermostatic device responsive to the temperature of the products of combustion and acting to move the damper from a position of running or maximum draft toward a position of minimum draft upon a fall in temperature. A further object is the correlation of a draft damper control system of this type with an air control damper also controlled in accordance with the temperature of the products of combustion.

Another object of the invention is the provision of a draft damper control system embodying a relatively quick acting control device and a relatively slow acting device, which devices cooperate to cause movement of the damper in a predeter-

mined sequence relative to stopping and starting of the stoker or burner.

A further object of the invention is the provision of a control system for a burner and a draft control damper which acts after normal stopping of the burner to cause movement of the damper to a position of minimum draft, but which acts upon stopping of the burner due to an abnormal condition to maintain the draft control damper in a position of substantial draft.

Other objects of the invention consist in the provision of various novel combinations and sub-combinations of control apparatus and will become apparent from the following description and the appended claims.

For full disclosure of this invention reference is made to the following detailed description and to the accompanying drawings in which:

Fig. 1 illustrates diagrammatically an application of the invention to a control system for a large boiler installation;

Fig. 2 is a fragmentary view showing the air control damper of Fig. 1 in detail;

Fig. 3 shows diagrammatically an application of the invention to a boiler or furnace of relatively small size;

Fig. 4 is a section taken on line 4-4 of Fig. 3;

Fig. 5 is an elevational view partly in section of the stoker air control of Fig. 3;

Fig. 6 shows a modified form of stoker air control;

Fig. 7 shows diagrammatically another form of the invention; and

Fig. 8 is an elevational view partly in section of the stoker air control of Fig. 7.

Referring to Fig. 1, reference character 1 indicates a boiler or furnace which may be used in industrial or semi-industrial applications such as for supplying steam or heating buildings or for processing. This boiler is fired by a combustion producing means such as a stoker having a retort 2, a hopper 3, a fuel feed screw 4 and an air supply duct 5. This stoker may be driven by a motor 6 which serves to operate the feed screw and a blower 7 which forces air through the air duct 5. The stoker is also provided with a flow control device for controlling the flow of air to the fuel bed, this device being indicated at 8.

This air control device is shown in Fig. 2 and may consist of a damper blade 9 which is pivoted at 10 to the air duct, the damper blade 9 thus being adapted to open under the influence of air pressure from the stoker blower. When the stoker is out of operation this damper assumes the position shown for preventing the flow of air to the stoker by natural draft. This damper is provided with an arrangement for maintaining it in the open position when it is forced to this position by the air delivered from the blower. This holding means may consist of a lever 11 which is attached to the damper 9, this lever 11 being adapted to engage a flexible latch member 12. The latch member 12 may be carried by the armature 13 of a relay having a coil or electromagnet 14. When the relay coil 14 is energized the armature 13 is attracted to it thus causing the latch member 12 to assume the position shown in dotted lines. When the damper 9 is blown to the open position, shown in dotted lines, the lever 11 also assumes the position shown in dotted lines and is latched in this position by the latch member 12. Thus when the stoker is placed out of operation the damper 9 will be held in open position until the relay coil 14 is deenergized. At this time the armature 13 will rotate clockwise

under the action of a suitable spring such as 15, this causing the latch member 12 to release the lever 11 and permit the damper to close.

The furnace 1 is also provided with the usual flue or breaching for conveying the products of combustion to a stack 17. Located in this flue is a draft control device or breaching damper 18, this damper being positioned by a reversible electric motor 19. This motor 19 is controlled by a draft controller generally indicated as 20 and also by relays generally indicated as 21 and 22.

Referring to the draft controller 20, this device may be of any suitable construction and is illustrated as comprising a diaphragm 23 closing one side of housing 24, the interior of which communicates through a draft tube 25 with the flue 16 ahead of damper 18. The diaphragm 23 is thus subjected to the sub-atmospheric pressure or draft within the flue 16 and hence within the combustion chamber of the furnace 1. The tube 25 may obviously be connected at other points than the flue 16, such, for example, as directly with the interior of the combustion chamber. The diaphragm 23 may actuate a suitable operating member 27 which actuates switch arms 28 and 29. A biasing spring 30 may bias the diaphragm 23 against atmospheric pressure, this spring having an adjusting screw 31. The switch arm 28 may cooperate with a pair of opposed contacts 32 and 33 which are resiliently supported on contact blades as shown. This switch arm 28 and contact blades 32 and 33 form a minimum draft control switch. The switch arm 29 cooperates with opposed contacts carried by flexible contact blades 35 and 36 to form a second draft control device which is adapted to maintain a higher draft (lower pressure) than the first mentioned draft control device. The switch arm 28 and its associated contacts are placed in control 35 of the damper motor 19 when the stoker is out of operation for maintaining a minimum draft at this time. The switch arm 29 and its associated contacts are placed in control of the damper motor when the stoker is in normal operation and serve 40 to control motor 19 for maintaining a predetermined draft which provides maximum combustion efficiency.

Referring to the relay 21, this relay includes an electromagnet including a coil 40 which operates a suitable armature 41 actuating the switch arm 42. The switch arm 42 is adapted to engage an overlapping type of contact mechanism which is shown as comprising a movable contact 43 carried by a contact blade 44 which in turn 45 is biased against a fixed contact 45. When the relay coil is deenergized the switch arm assumes the position shown wherein it is disengaged from contact 43. At this time the contact blade 44 engages the fixed contact 45. When the relay coil 40 is energized the switch arm 42 first engages the contact 43 and then causes movement of the contact blade 44 in a clockwise direction thereby disengaging this contact blade from the fixed contact 45. By this arrangement the switch arm 42 always engages the contact 43 before the contact blade 44 disengages stationary contact 45. The relay 21 also includes a second switch arm 47 which is adapted to selectively engage an "out" contact 48 and an "in" contact 49. The relay 22 includes a coil 50 which operates through a suitable armature a pair of switch arms 51 and 52, the switch arm 51 cooperating with an "in" contact 53 and the switch arm 52 cooperating with 55 an "in" contact 54 and an "out" contact 55. The

control system also includes a motor relay generally indicated as 57, this relay including a coil 63 which operates through a suitable armature a pair of switch arms 58 and 59. The switch arm 58 controls the stoker motor 6, this switch arm engaging a fixed contact 60 when the relay coil 50 is energized and being disengaged from this fixed contact when the coil 50 is deenergized. The switch arm 59 cooperates with an "out" contact 61 and an "in" contact 62.

Reference character 65 generally indicates a timing device which preferably is of the thermal type having a bimetallic element 66 secured to a fixed support 67 and having its free end cooperating with a fixed contact 68. The bimetallic element 66 is arranged so that it engages the fixed contact 68 as shown when the element is relatively cold. This bimetallic element 66 is heated by means of a heater 69 and under the influence of this heater moves downwardly so as to disengage the fixed contact 68.

Referring again to the damper motor 19, this motor may be of the type shown in the Cummings patent, No. 1,895,880. This is a motor of the shaded pole type having power supply wires 70 and a 3-wire control circuit comprising wires 71, 72 and 73. When an electric circuit is completed from wire 71 to wire 72 the motor operates in a direction for opening the damper 18. When an electric circuit is completed from wire 72 to wire 73 the motor 19 operates in a direction for closing damper 18. When wire 72 is disconnected from both wires 71 and 73, the motor remains at rest in whatever position it happens to be. This motor is preferable provided with built-in limit switches which stop the motor when the damper reaches either wide open position or closed position. The damper motor 19 is also provided with an auxiliary switch indicated generally at 75. This auxiliary or damper switch is shown diagrammatically as comprising a movable contact blade 76 which is adapted to be forced into engagement with a fixed contact 77 by an extension 78 on the lever arm of the damper motor. When the damper 18 is in wide open position the switch arm 76 engages contact 77. However for all other positions of the damper the switch arm 76 is disengaged from contact 77.

The stoker and the draft damper are controlled by a heat demand responsive device 80. This device may be a thermostat if the boiler is supplying steam for heating purposes, or may be a pressure responsive device or any other type of control device which closes a circuit when heat is required from the boiler or furnace 1. The stoker is additionally controlled by a high limit control 81 which is shown mounted upon furnace 1. This device may be a thermostat or pressure control which includes a switch which is opened whenever the pressure or temperature of heater 1 rises beyond a predetermined value.

Operation of Figure 1

With the parts in the position shown the device 80 is satisfied, the relays 21, 22 and 57 all being deenergized. At this time the switch arm 28 of the draft controller 20 is connected to the common control wire 72 of damper motor 19 as follows: Wire 72, selector switch arm 83, selector switch contact 84, wire 85, switch arm 52, contact 55, wire 86, switch arm 47, contact 48 and wire 87 to switch arm 28. The draft (suction) within the furnace is at the proper stand-by value as indicated by the switch arm 28 being disengaged from contact arms 32 and 33. If the

5 draft should fall below the desired value the diaphragm 23 will move outwardly bringing switch arm 28 into engagement with the contact 33. This contact, it will be noted, is connected by 10 wires 88 and 89 to the wire 71. Thus engagement of switch arm 28 with contact 33 will connect the motor control wires 71 and 72 together which causes operation of the motor 19 in a direction for opening damper 18. This opening of damper 18 will permit a greater flow of air from the flue into the stack thus increasing the draft (decreasing the pressure) within the furnace combustion chamber. When the draft is increased to the proper value the switch arm 28 disengages contact 33 and the damper motor 19 stops with the damper in the new position. If the furnace draft becomes too high the switch arm 28 will engage contact 32 which contact is connected to the motor control wire 73 by wires 90 and 91. Thus 15 at this time the motor control wires 72 and 73 are connected together which causes operation of the motor 19 in a direction for closing the damper 18. This movement of the damper continues until the draft is increased to the desired value 20 at which time the switch arm 28 disengages contact 32 for stopping the motor with the damper in a new position. From the foregoing it will be seen that when the device 80 is satisfied and the stoker is out of operation the draft controller 20 serves to control the damper motor 19 in a manner to maintain a predetermined low draft.

When the device 80 calls for heat a circuit will be completed for energizing coil 40 of relay 21 as follows: From secondary 93 of transformer 94, wire 95, control device 80, wire 96, wire 97, contact 45, switch blade 44, wire 98, wire 99, relay coil 40, wire 100, bimetal element 66 and wires 101 and 102 to secondary 93. When the switch arm 42 of relay 21 engages contact 43 it completes a holding circuit for coil 40 as follows: From secondary 93, wire 95, wire 103, switch arm 42, switch blade 44 and wires 98 and 99 to relay coil 40. After the switch arm 42 engages contact 43 the switch blade 44 disengages contact 45. Thus 25 when the relay 21 is pulled in the starting circuit for the relay coil is broken and the coil is maintained energized by an independent holding circuit, this holding circuit serving to connect the wire 98 directly to the transformer secondary 93. At this time the coil 50 of relay 22 is also energized by a circuit extending from the wire 98 through coil 50, wire 105, contact 61, switch arm 59 and wires 106 and 102 to secondary 93. The coil 63 of relay 57 at this time remains deenergized so that the stoker remains at rest. Due to the switch arm 52 of relay 22 now engaging its "in" contact 54 a circuit is completed from control wire 72 of damper motor 19 to control wire 71 as follows: Wire 72, selector switch arm 83, selector switch contact 84, wire 85, switch arm 52, contact 54 and wire 107 to wire 71. This causes the damper motor 19 to run in damper opening direction irrespective of the draft controller 20. The damper motor now runs to move the damper to wide open position at which time it is stopped by a built-in limit switch, not shown. When the damper reaches this wide open position the auxiliary or draft switch 75 is closed which completes a starting circuit for relay coil 63 as follows: From secondary 93, wire 95, control device 80, wire 96, wire 108, coil 63, wire 109, contact 77, switch arm 76 and wires 110 and 102 to secondary 93. When the relay 57 pulls in its switch arm 58 engages contact 60 which energizes the stoker motor 6 as follows: From line wire 111,

contact 60, switch arm 58, wire 112, limit control 81, wire 113, and motor 8 to line wire 114. The stoker is thus placed into operation. Also when relay 57 is energized its switch arm 59 disengages contact 61 and engages contact 62. When switch arm 59 disengages contact 61 it breaks the energizing circuit for coil 50 of relay 22, thus causing this relay to drop out. When the switch arm 59 engages contact 62 it completes a holding circuit for relay coil 63 which is independent of the damper switch 75, this circuit extending from wire 108, through coil 63, contact 62, switch arm 59, and wires 106 and 102 to secondary 93. The damper 18 may therefore now be moved away from wide open position without affecting relay 57. As mentioned above when the relay 57 becomes energized it, in addition to establishing a holding circuit for itself, also deenergizes the coil 50 of relay 22. As a result the switch arm 52 of this relay engages its "out" contact 55. At this time it will be noted that relay 21 remains energized thus causing its switch arm 47 to engage contact 49. A circuit is thus completed from the control wire 72 of motor 19 to the switch arm 29 of the draft control 20 as follows: From wire 72, switch arm 83, contact 84, wire 85, switch arm 52, wire 86, switch arm 47, contact 49, and wire 115 to switch arm 29. It will be noted that the contact arms 35 and 36 cooperating with the switch arm 29 are connected to the motor control wires 73 and 71 respectively. The draft controller 20 therefore now controls the damper motor 19 in a manner to maintain a predetermined draft for providing maximum efficiency of combustion.

The solenoid 14 of the stoker air damper 8 is connected to wires 98 and 102. Consequently as long as the relay 21 is energized this solenoid is energized. When the stoker motor 8 is started the air from the fan 7 forces the air damper 9 to open position and due to the solenoid 14 being energized at such time this damper is latched in open position as shown in the dotted lines of Fig. 2.

From the description thus far it will be apparent that during the stand-by periods, that is when the control device 80 is satisfied, the draft controller 20 serves to control the damper motor in a manner to maintain a predetermined minimum draft. However, when the control device 80 calls for heat the relays 21 and 22 are energized, the relay 22 taking control of the damper motor away from controller 20 and causing the damper to be operated to wide open position during which time the stoker remains at rest. When the damper motor reaches wide open position the closure of the damper switch 75 energizes the relay 57 which places the stoker into operation and deenergizes the relay 22, this returning the control of the damper motor 19 to the draft controller 20, the relay 21 causing the high draft control switch of this draft controller to be effective so as to maintain a relatively high draft while the stoker is in operation. Also the stoker air damper 9 is blown upon by the air from the fan 7 and is latched in open position due to the solenoid 14 being energized.

When the control device 80 becomes satisfied it will open its switch which deenergizes the coil of relay 57. This relay thus drops out and stops the stoker. The switch arm 59 of this relay now engages its "out" contact 61 which once more completes the energizing circuit for coil 50 of relay 22 which has previously been traced. It will be noted that due to the switch arm 42 of

relay 21 engaging contact 43 the relay coils 40 and 50 are connected to secondary 93 independently of the control device 80. Thus when the control device 80 becomes satisfied and causes relay 57 to drop out, the relay coil 40 remains energized and the relay coil 50 becomes energized due to the dropping out of relay 57. When the coil 50 of relay 22 becomes energized the switch arm 52 thereof engages contact 54 which once more directly connects control wires 71 and 72 of the damper motor 19 which causes this motor to run the damper to wide open position irrespective of the draft controller 20. When the damper reaches wide open position the damper switch 75 is once more closed and due to the switch arm 51 of relay 22 now engaging contact 53 the heater 69 of timer 65 is energized as follows: From secondary 93, wire 95, wire 103, heater 69, contact 53, switch arm 51, wire 109, damper switch 75 and wires 110 and 102 to secondary 93. From the description thus far it will be apparent that when the control device 80 becomes satisfied the stoker is immediately stopped. However, the solenoid 14 of the stoker air damper 9 remains energized which causes the air damper to remain latched in open position. Also when the stoker is placed out of operation the flue damper 18 is operated to its wide open position irrespective of the draft controller for maintaining a maximum draft. Also when the damper reaches its wide open position the heater 69 of the thermal timer 65 becomes energized. Due to the dampers 8 and 18 both being in open position a maximum natural draft is provided when the stoker is first placed out of operation. This natural draft serves to provide for good combustion of the green coal remaining in the stoker retort and consequently reduces smoking of the fire to a minimum. In addition the opening of damper 18 insures that whatever smoke is emitted from the fire due to improper combustion of the green coal is drawn into the stack and thus prevented from escaping into the boiler or furnace room.

After a period of time the volatile matter in the green coal is burned off and thus the tendency to smoke disappears. The thermal timer 65 is adjusted so as to open its contacts upon the expiration of the period of time required for burning off this volatile matter. At this time the bimetallic element 66 due to the influence of heat from the heater 69 disengages contact 68. This breaks the energizing circuit for coil 40 of relay 21 which causes the switch arm 42 to disengage contact 43 and causes switch arm 47 to engage contact 48 as shown. Due to the switch arm 42 disengaging contact 43 the energizing circuits for relay coil 50 and solenoid 14 are broken. Deenergization of solenoid 14 causes the latch member 12 to disengage lever 11 thus permitting damper 9 to close and stop or reduce to a minimum the natural draft to the fuel bed. This reduces the rate of burning of the fuel to a minimum. Deenergization of coil 50 of relay 22 causes the switch arm 51 to disengage contact 53 which breaks the energizing circuit for heater 69. The switch arm 52 of relay 22 in disengaging contact 54 and engaging contact 55 places the switch arm 28 of draft controller 20 in control of the damper motor and thus causes the damper 18 to be returned from the wide open position to whatever position is necessary for maintaining the minimum predetermined draft. The draft controller 20 now maintains the furnace draft at a minimum until the device 80

again calls for heat at which time the control cycle described above is repeated.

At some times it is desirable to open the damper 18 wide irrespective of the automatic control system. In such event the manual switch arm 83 is moved from the contact 84 into engagement with contact 116 which directly connects control wires 71 and 72 together. At other times, such as when the boiler is out of service, it is desirable to close the damper 18 completely. At such time the manual selector switch arm 83 may be moved into engagement with the contact 117 which directly connects motor control wires 72 and 73, this causing the motor to operate the damper to closed position.

From the foregoing description it will be apparent that during the stand-by periods when the control device 80 is satisfied the stoker is out of operation, the air damper 9 is closed for reducing the rate of combustion to a minimum and the flue damper 18 is under automatic control for maintaining a minimum draft. When the device 80 calls for heat, the first result is the opening of the flue damper 18 to wide open position. When the damper actually reaches wide open position, and not until then, the stoker is placed into operation and the damper motor is again placed under the control of the draft regulator which now serves to maintain a predetermined relatively high furnace draft which provides for proper combustion. When the device 80 becomes satisfied it stops the stoker. However the air damper 9 remains in open position and the flue damper 18 is operated to its wide open position. These two dampers remain in open position for a substantial period of time which is sufficient to burn off the volatile matter of the green coal in the stoker retort, this arrangement thus minimizing smoking of the fire upon stopping of the stoker and insuring that any smoke emitted from the fire does not escape into the furnace room. When the volatile matter of the green coal is burned off the air damper 9 is closed and the flue damper 18 is returned to control by the draft controller 20 which once more serves to maintain a minimum or stand-by draft.

In some installations it may be desired to operate the flue damper 18 to a fixed closed or minimum position during the stand-by period instead of a variable position. In such event the switch 28-32-33 of the draft controller 20 may be omitted, the wire 87 being directly connected to the control wire 73 of the damper motor. In other installations it may be desirable to maintain the same draft during the stand-by periods as during the running periods of the stoker. In such case the low draft control switch of the draft controller may be omitted and also the relay switch arm 47 and contacts 48 and 49 may be omitted. In this case the contact 55 of relay 22 would be directly connected to the draft control switch arm 29.

Figures 3, 4 and 5

Referring now to Fig. 3, this figure discloses an application of the invention to a smaller boiler or furnace such as used for heating residences or small buildings. In this figure the furnace 120 is provided with a stoker having a retort 121, a feed screw 122, an air duct 123 and a housing 124 containing the usual coal hopper and operating mechanism, such as motor 125 and fan 126. The stoker is also provided with an air control generally indicated as 127 and which

is diagrammatically shown in Fig. 5. Referring to this figure, the air control device 127 may include a butterfly type damper blade 128 which is pivoted to the sides of the air duct at 129. This damper blade is attached by a link 130 to a vane 131, the link 130 passing through an opening 132 into the interior of a control housing 133 which is secured to the air duct 123 and which contains the vane 131. The vane 131 fits closely to the sides of the housing 133 and is pivoted to the housing at 134. The free end of this vane lies closely adjacent an arcuate member 135 which is fixed to the side walls of housing 133, this member 135 having a curvature concentric with the path of movement of the free end of vane 131. This arcuate member 135 may carry a stop 136 at its upper end for preventing over-travel of vane 131. The vane 131 is attached by a spring 137 to the free end of a bimetal element 138 by means of an adjusting screw 139. The bimetal element 138 may be supported by a U-shaped bracket 140 which is secured to the side of housing 133, this bracket being provided with an adjusting screw 141 for adjusting the position of bimetal element 138 with respect to the housing 133. This bimetal element 138 is provided with a heater 142, which heater is energized when the stoker is placed into operation. When the heater 142 is cold, as during a stand-by period, the bimetal element 138 assumes the position shown in which it applies a slight compressive force to the spring 137, this forcing the vane 131 downwardly and forcing the damper blade 128 to closed position. When the stoker is started the heater 142 is energized, but the bimetal element 138 requires an appreciable time to heat. Thus when the stoker first starts, the damper 128 is held in closed position so as to restrict the flow of air to the retort. As the bimetal element 138 becomes heated it warps upwardly, this removing the compressive force from spring 137 and now applying tension to this spring for pulling vane 131 upwardly thus opening the damper 128. As damper 128 opens the pressure on the down-stream side rises, this pressure building up under vane 131, thus forcing the vane 131 upwardly against spring 137. The air leaking around the edges of the vane 131 passes from the housing 133 through an adjustable opening 144 in the cover for this housing and thus the pressure at the top of vane 131 remains substantially atmospheric. The bimetal element 138 when fully heated engages a stop 143. At this time the air control device 127 functions to maintain the proper supply of air to the retort as to maintain the fuel bed at the desired thickness and thus proportions the air flow with the fuel feed. Thus if the air flow is more than necessary to burn the coal in the retort, the thickness of the fuel bed will decrease which decreases the resistance to flow of air therethrough. This would normally result in still further increasing the flow of air to the retort. However, as the resistance to air flow through the fuel bed decreases, the pressure on the down-stream side of the damper 128 decreases correspondingly which causes the vane 131 to lower under the action of gravity and/or spring 137 thereby reducing the flow of air to the retort. Conversely, if the rate of air supply is not enough to burn the fuel supplied to the retort, the thickness of the fuel bed increases, which increases the resistance to flow of air through the fuel bed, thus causing increase in the pressure of the air supplied. This increase in pres-

sure urges vane 131 upwardly until the spring 137 is compressed sufficiently to resist further movement, this motion of the vane 131 causing opening movement of the damper 128 for increasing the supply of air to the retort. It should now be apparent that the function of the air control device 127 is to delay the supply of air to the stoker when the stoker is first started, this having the effect of preventing or substantially reducing fly ash. When the stoker has operated a short time so that new fuel is delivered to the retort and the danger of fly ash eliminated, the air damper 128 is gradually opened and during normal operating of the stoker is variably positioned so as to proportion the air supply to the fuel feed. When the stoker is placed out of operation the heater 142 is de-energized. However due to the residual heat of the bimetal element 138, this element stays in its hot position for a substantial period of time which maintains the damper 128 in at least partially open position. For a more complete description of the stoker air damper of Fig. 5, reference is made to the application of Clifford Hotchkiss, Serial No. 350,715, filed August 3, 1940.

In Fig. 3 the flue damper may be of the so-called barometric type, this damper being located in an air inlet to the flue and serving to regulate the pressure in the flue by varying the amount of air admitted. This damper may be of any suitable type and is shown diagrammatically as comprising a damper blade 145 which is pivoted off center in an air passage 146 of a damper housing 147 in flue 148. In Fig. 3 the damper mechanism is shown for convenience as having the air inlet passage 146 extending from the bottom of the flue. In actual practice, however, the damper 145 and its passage should be located at one side of the flue so that the axis of rotation of the damper 145 is substantially vertical. The damper 145 is positioned by the conjoint action of a solenoid 150 which may be mounted on the damper housing, this solenoid cooperating with an armature 151 which is pivoted at 152, this armature operating an abutment lever 153 which is arranged to abut a lever 154 attached to the shaft of the barometric damper 145. The lever 153 is biased in a clockwise direction by means of a spring 156. When the solenoid 150 is energized it attracts the armature 151, causing counterclockwise rotation of lever 153 against the tension of spring 156, the lever 153 in turn causing clockwise rotation of the lever 154 and movement of the damper 145 to its completely closed position. When the solenoid 150 is de-energized the parts assume the position shown in which the damper 145 may open completely. The damper operating lever 154 also may be actuated by a resilient or yieldable abutment lever arm 158 which is attached to the shaft 159 (Fig. 4) of a stack temperature responsive device which may include a spiral bimetallic element 160. When the temperature at thermostat 160 is at a value such as 125° F. indicating that the stoker is out of operation, and when the solenoid 150 is de-energized, the yieldable lever arm 158 assumes the position shown in which it forces the barometric damper 145 to its wide open position. However, when the temperature at thermostat 160 rises to a higher value indicating operation of the stoker, the lever arm 158 rotates counterclockwise thereby leaving the damper 145 free to adjust itself for maintaining the predetermined draft. The shaft 159 also operates a suitable form

of switching mechanism in accordance with the temperature of the products of combustion. This switching mechanism is illustrated diagrammatically as comprising an arm 162 attached to shaft 159 and to an insulating member 163 which operates switch arms 164 and 165, these switch arms engaging contacts 166 and 167 respectively when the stack temperature is low and engaging contacts 168 and 169 respectively when the stack temperature is high. Preferably the actuation of switch arms 164 and 165 is effected with snap action by suitable means diagrammatically illustrated as a permanent magnet 170.

The control system of Fig. 3 additionally includes a heat demand responsive device such as 172 which in this case might be a thermostat responsive to the temperature of a space heated by the furnace 120. This thermostat may be of a type well known in the art which closes its contacts upon fall in temperature to a predetermined value and which opens its contacts upon rise in temperature above such value. This thermostat may also include an anticipating heater 173 which functions to add false heat to the thermostat during a call for heat thereby shortening the length of the "on" periods of the stoker. This thermostat controls a relay generally indicated as 174 which includes a coil 175 which operates through a suitable armature a pair of switch arms 176 and 177. When the coil 175 is energized the switch arm 176 engages a contact 178 and the switch arm 177 engages a contact 179. When the relay coil is de-energized the switch arm 177 engages a contact 180 and the switch arm 176 is disengaged from contact 178.

Operation of Figures 3, 4 and 5

With the parts in the positions shown the thermostat 172 is satisfied as indicated by its contacts being open. The relay 174 is also de-energized which causes the stoker to be out of operation and which also causes the solenoid 150 of the stack damper control to be de-energized. The temperature of the stack gases is also relatively low as indicated by the stack thermostat assuming a position in which it forces the barometric damper 145 to wide open position and causes the switch arms 164 and 165 to engage contacts 166 and 167 respectively. The bimetallic element 138 of the air damper control 127 is also cold which causes the air damper 128 to be closed.

If the thermostat 172 now calls for heat it will close its contacts and energize the relay coil 175 as follows: From secondary 181 of transformer 182, wire 183, thermostat 172, wire 184, coil 175 and wire 185 to secondary 181. The energizing current for the relay also passes through the anticipating heater 173 for causing false heat to be applied to the room thermostatic element. Energization of coil 175 causes switch arm 176 of relay 174 to engage contact 178 which energizes the stoker motor 125 as follows: From line wire 186, contact 178, switch arm 176, wire 187, high limit control 188, wire 189 and motor 125 to line wire 190. Energization of coil 175 also causes the switch arm 177 to engage contact 179 which immediately energizes the heater 142 of air damper control 127 as follows: Secondary 181, wire 191, wire 192, switch arm 177, wire 193, wire 194, contact 166, switch arm 164, wire 195, heater 142 and wire 196 to secondary 181. Thus the heater 142 is energized simultaneously with the stoker motor. At the same time the solenoid 150 of the flue damper control is energized as follows: Secondary 181, wire 191, wire 192, switch arm 177,

contact 179, wire 193, contact 167, switch arm 165, wire 198, solenoid 150, wire 199 and wire 196 to secondary 181. Energization of solenoid 150 causes the armature 151 to be attracted, thereby rotating lever 153 counterclockwise against the action of spring 156, this in turn rotating the damper lever 154 so as to substantially or completely close the barometric damper 145. At this time the lever 158 yields and thus permits the damper to close even though the stack temperature is low.

From the description thus far it will be apparent that when the thermostat 172 calls for heat it starts the stoker, energizes heater 142 of the air damper control and energizes the solenoid 150 of the flue damper control which causes the barometric damper to be moved from wide open position to completely closed position. The bimetal element 138 of the air damper control 127 requires an appreciable time to heat, for example, a minute or two. Thus when the stoker is first started the air delivery to the stoker retort is prevented or maintained at a minimum while the barometric damper is held closed. This delay in supplying air to the stoker permits a certain amount of coal to be fed to the stoker retort thus building up an appreciable fuel bed before air is supplied. The purpose of this delay in air supply is to avoid fly ash. If the fire has burned down during a stand-by period to a considerable extent the resistance of the fuel bed would be quite low and ash would be blown from the retort if the air were delivered thereto immediately upon starting of the stoker. By delaying the supply of air the stoker is given an opportunity to feed some coal into its retort before air is delivered thereto, this increasing the resistance of the fuel bed and preventing or substantially reducing fly ash when the air supply is commenced. At the same time the barometric damper being completely closed provides maximum draft and also closes communication between the furnace room and the flue during this starting period. This provision of maximum draft insures that no products of combustion will enter the furnace room if for some reason the stack draft is very low due, for example, to the stack being cold. This arrangement also permits the barometric damper to be adjusted to maintain a lower draft than would otherwise be possible. In other words, in prior barometric damper installations the damper cannot be adjusted to maintain the ideal draft as such a setting would result in the damper opening too easily, permitting products of combustion to be discharged into the furnace room if the stack is cold. The present arrangement, however, permits the damper to be adjusted for maintaining the ideal draft and at the same time prevent discharge of products of combustion into the furnace room.

After the stoker has operated a short time the bimetal element 138 of the air control 127 will become heated which causes opening of the air damper 128 and the automatic positioning of this damper for proportioning the air supply to the fuel feed in the manner previously described. This operation of the stoker will result in the temperature of the products of combustion rising which will cause the stack thermal element 160 to rotate the arms 158 and 162 in a counter-clockwise direction. This rotation of lever 158 causes it to swing clear of the damper lever 154. Corresponding rotation of lever 162 causes the switch arms 164 and 165 to be disengaged from contacts 166 and 167 and to be brought into engagement

with contacts 168 and 169 respectively. Disengagement of the switch arm 165 from contact 167 deenergizes the solenoid 150 which causes the lever 153 to be swung clear of the damper lever 154. The barometric damper 155 is now free to float and thus position itself for maintaining the draft for which it is adjusted. Disengagement of the switch arm 164 from contact 166 and engagement thereof with contact 168 establishes a new energizing circuit for the heater 142 of the air damper control, this new circuit being independent of the relay 174 and as follows: Secondary 181, wire 200, contact 168, switch arm 164, wire 195, heater 142 and wire 196 to secondary 181.

The stoker will now operate with the air damper control 127 automatically proportioning the supply of air and the barometric damper 145 automatically maintaining a constant draft. As a result the stoker will operate at maximum efficiency. When the thermostat 172 opens its contacts the relay 174 will be deenergized, the switch arm 176 becoming disengaged from contact 178 for stopping the stoker. The switch arm 177 will also engage contact 180 which will establish a new energizing circuit for solenoid 150 as follows: From secondary 181, wire 191, wire 192, switch arm 177, contact 180, wire 201, contact 169, switch arm 165, wire 198, solenoid 150, wire 199 and wire 196 to secondary 181. Thus when the stoker is first placed out of operation the barometric damper 145 is moved to closed position by energization of relay 150, this relay now being energized due to the stack thermostat being in its hot position. Also the heater 142 of the air control 127 remains energized due to the stack thermostat being in its hot position. Consequently upon stopping of the stoker the draft is increased to a maximum and the air damper is maintained open which permits a supply of air to the stoker by natural draft. This provides for burning off the volatile matter of the green coal in the stoker retort without substantial smoking and also insures that any smoke emitted is prevented from passing into the furnace room through the check damper passage.

Due to the stoker being out of operation the stack temperature will fall after a period of time, thus causing the stack arms 158 and 162 to return to positions shown in Fig. 3, the switch arms 164 and 165 being disengaged from contacts 168 and 169 and being reengaged with contacts 166 and 167. Disengagement of the switch arms 164 and 165 from contacts 168 and 169 will deenergize the solenoid 150 and also the heater 142 of the air damper control. The reengagement of these switch arms with contacts 166 and 177 will have no effect due to switch arm 177 of relay 174 being now disengaged from contact 179. Deenergization of solenoid 150 will permit the resilient stack arm 158 to move the check damper from completely closed position to open position. Deenergization of the heater 142 will permit the bimetal element 138 to cool for closing the air damper 128. Thus the draft during the stand-by period will be reduced to a minimum and also the air damper will be closed which reduces burning of the fire by natural draft to a minimum. This substantially reduces the heat delivered by the stoker during the "off" or stand-by periods and also retards the fire from burning out at this time.

From the foregoing description it will be apparent that during the "off" periods of the thermostat 172 the stoker is out of operation, the air damper is closed and the barometric or flue damp-

er is wide open. When the thermostat calls for heat the barometric damper is immediately moved from wide open position to completely closed position, and while the heater 142 is immediately energized a substantial period of time is required before the air supply damper begins to open. Thus the stoker is operated for a short period of time with a reduced air supply and with the barometric damper completely closed for providing maximum draft. After a short period the air control damper opens and assumes automatic operation in which it proportions the flow of air to the fuel feed. Also the stack temperature rises which causes the barometric damper to be placed under automatic control for maintaining a constant draft. When the stoker is placed out of operation the barometric damper is immediately closed and the air damper is maintained in open position, the dampers being held in these positions until the stack temperature falls, at which time the air damper is permitted to close and the barometric damper is moved from closed position to wide open position.

It will be noted that the heater 142 of the air damper control is energized immediately upon energization of relay 174, this result being provided by the switch arm 164 and contact 166 of the flue damper control. This arrangement is desirable in installations where the air damper permits sufficient flow of air to cause the fire to pick up and in installations where an anticipated type of thermostat is used or when some other form of heat demand responsive control is employed which provides fairly short "on" periods. It will be apparent that if the air control is designed to prevent any material flow of air until the heater 142 is energized, the stack temperature might not rise sufficiently to cause energization of this heater. It will also be apparent that when the "on" periods are fairly short the combined time delay of the stack thermostat and that of the bimetal element 138 might be longer than the "on" period and thus the stoker air damper would never open. By the arrangement described, however, the heater 142 is energized simultaneously with the stoker which insures that the air damper opens before the "on" period of the thermostat has expired. In installations in which the "on" periods are sufficiently long and in which a substantial flow of air may occur when the air control damper is in its minimum position, the heater 142 may be controlled solely by the stack thermostat, being energized when the stack temperature rises and being deenergized when the stack temperature falls. In other words, the arrangement for energizing the heater 142 through the "in" contact 179 of relay 174 and "cold" contact 166 of the stack damper control may be omitted.

In some applications of the invention it may be desirable to design the bimetallic element 138 and heater 142 so that the element 138 both heats and cools very slowly. In this event the heater 142 could be controlled directly by the relay 174, the stack thermostat contacts thus being omitted. In other words, instead of positively holding the air damper open until a fall in stack temperature occurs, the air damper control may be designed so as to require a substantial period of time in closing the damper such as will usually permit the volatile matter in the green coal to be consumed.

It will also be apparent that in low priced installations the solenoid 150 may be omitted. In this case the barometric damper would be con-

trolled solely by the stack thermal element which also controls the air damper.

If desired a solenoid and armature may be substituted for the bimetal element 138 and heater 142 of the stoker air damper. This modification is shown in Fig. 6. In this figure the construction of the air damper is substantially the same as in Fig. 5 except that a lever 210 is substituted for the bimetal element 138, this lever being pivoted at one end and carrying an armature cooperating with a solenoid 212 attached to the top of the housing. The solenoid 212 may be connected to the wires 195 and 196 of Fig. 3. This arrangement will operate in the same manner as the arrangement first described with the exception that no delay in air feed will be provided, which is satisfactory for certain types of installations. If a delay in air feed is desired while at the same time utilizing a solenoid type air control this result may be obtained by omitting the contact 166 of Fig. 3 so that a rise in stack temperature must occur before the air damper is moved from its minimum position.

Figures 7 and 8

Another form of the invention may take is shown in Figs. 7 and 8. In Fig. 7 the furnace 215 is provided with a stoker as in the modifications previously described, this stoker having a motor 216 and an air damper control generally indicated as 217. As shown in Fig. 8 the stoker air control 217 may be of generally the same construction as the air control 127 of Fig. 5. In this case, however, the bracket 218 which supports the bimetal element 219 is formed of insulating material and actuates a suitable switching mechanism. This switching mechanism may comprise a pair of stationary contacts 220 and 221 which cooperate with contact points secured to the end of element 219. Preferably the bimetal element 219 operates at least the switching mechanism with snap action. This snap action may be provided by any suitable form of mechanism and is illustrated diagrammatically as comprising a permanent magnet 222 which is adapted to cooperate with an armature carried by bimetal element 219. The bimetal element 219 is heated by a heater 223 which is as shown in Fig. 7 connected directly across the terminals of motor 216 by wires 224 and 225. In this embodiment of the invention, therefore, the heater 223 is energized when the stoker is in operation and is deenergized when the stoker is out of operation. The heater 223 and the bimetal element 219 are preferably designed so that the heater 223 must be energized an appreciable time before the bimetal element 219 moves from its cold position in which it engages contact 221 and closes the air damper, to its hot position in which it causes opening of the air damper and engages contact 220. Also the bimetal element 219 is designed so as to require an appreciable time to cool off after the heater is deenergized whereby the air damper 226 is maintained in open position and the contact engaged for a substantial period of time after stopping of the stoker.

The furnace 215 is also provided with a barometric damper control unit generally indicated as 228. This unit includes a barometric damper 229 which during normal operation of the stoker serves to maintain a constant draft in the furnace. This damper 229 is at certain times controlled by electro-magnets 230 and 231. The electro-magnet 230 cooperates with an armature 232 which actuates an abutment lever 233 which is

arranged to abut a damper lever arm 234, the lever 233 being biased in a counter-clockwise direction by spring 235. The electro-magnet 231 is arranged to operate an abutment lever 236 which is also arranged to abut the damper lever 234 and which is biased in a clockwise direction by a spring 237. It will be noted that when both solenoids 230 and 231 are deenergized the abutment levers 233 and 236 assume the positions shown wherein the barometric damper 229 is held in substantially wide open position. When the solenoid 230 is deenergized and the solenoid 231 energized the levers 233 and 236 become substantially spaced apart, this giving a substantial range of free movement for the damper lever 234 which permits the barometric damper 229 to adjust itself so as to maintain the predetermined draft in the furnace. When solenoids 230 and 231 are both energized the damper lever 234 is urged in a clockwise direction and held in a position in which the barometric damper 229 is substantially closed. The stoker and flue damper unit may be controlled by means of a thermostat or pressure controller 240 which controls a relay generally indicated as 241, this relay including a coil 242 and switch arms 243, 244 and 245. When the coil 241 is energized the switch arms 243, 244 and 245 engage contacts 246, 247 and 248 respectively. When coil 242 is deenergized the switch arms 244 and 245 engage contacts 249 and 250 respectively.

Operation of Figures 7 and 8

With the parts in the positions shown, the control device 240 is satisfied and the relay 241 is deenergized. The stoker motor 216 is out of operation and the heater 223 of the air control unit 217 is deenergized. The bimetal element 219 is also cold, this element now engaging contact 221 and holding the air damper 226 in closed position. The solenoids 230 and 231 of the barometric damper unit are also both deenergized, causing the barometric damper 229 to be held in wide open position. Thus the air supply to the stoker is reduced to a minimum and also the draft is reduced to a minimum, thereby causing the fire in the retort to burn at a minimum rate.

When the device 240 calls for heat the coil 242 of relay 241 is energized as follows: From secondary 253 of the transformer 254, wire 255, control device 240, wire 256, relay coil 242 and wire 257 to secondary 253. Energization of coil 242 causes the switch arms 243, 244 and 245 to engage their respective "in" contacts 246, 247 and 248. Engagement of the switch arm 243 with contact 246 establishes an energizing circuit for the stoker motor 216 and the heater 223 of the stoker air control, this circuit extending through the high limit control 258. Engagement of the switch arm 244 with contact 247 energizes the solenoid 230 as follows: From secondary 253, wire 255, wire 260, bimetal element 219, contact 221, wire 261, contact 247, switch arm 244, contact 262, solenoid 230, wire 263 and wire 257 to secondary 253. Engagement of the switch arm 245 with contact 248 energizes solenoid 231 as follows: From secondary 253, wire 255, wire 260, wire 264, contact 248, switch arm 245, wire 265, solenoid 231 and wire 257 to secondary 253.

From the description thus far it will be apparent that when the control device 240 calls for heat the stoker motor is placed into operation, the heater 223 is energized and the solenoids 230 and 231 are energized. Energization of solenoids 230 and 231 causes the damper 229 to be moved from

wide open position to substantially closed position. At this time the bimetal element 219 is cold and requires a substantial period of time in which to heat. During this period of time the stoker air damper 226 is closed to at least a minimum position and the barometric damper 229 held in closed position.

After a period of time in which the stoker is given an opportunity to deliver coal to the retort, 10 the bimetal element becomes sufficiently heated to move from its cold position to its hot position in which it engages contact 220 and causes the air damper 226 to open and operate automatically for proportioning the flow of air to the retort in accordance with the requirements for such air. When the bimetal element 219 disengages contact 221 it breaks the energizing circuit for solenoid 230. The solenoid 231, however, remains energized as its circuit does not extend through the bimetal element 219. Consequently the damper lever 234 is freed from contact with the abutment lever arms 233 and 236 and thus left free to position itself so as to maintain the draft for which it is adjusted. Thus after the stoker has operated for a period of time the air damper 226 is freed for automatic control and also the barometric damper 229 is freed for automatic control. This operation in which the air supply and draft are controlled automatically continues until the control device 240 becomes satisfied. At this time the relay 241 becomes deenergized thus stopping the stoker motor 216 and deenergizing the heater 223. The switch arms 244 and 245 now engage their "out" contacts 249 and 250, this causing energization of both solenoid 230 and solenoid 231 through the contact 220 of the stoker air control unit. Thus solenoid 230 is energized as follows: From secondary 253, wire 255, wire 260, bimetal element 219, contact 220, wire 266, wire 267, contact 249, 25 switch arm 244, wire 262, solenoid 230, wire 263 and wire 257 to secondary 253. The energizing circuit for solenoid 231 extends from wire 266 through contact 250, switch arm 245 and wire 265 to solenoid 231. When the stoker first stops the bimetal element 219 is heated to an appreciable extent and remains in its hot position for a substantial period of time after the heater 223 becomes deenergized. Thus the air damper 226 is held in open position and also the solenoids 230 and 231 are both energized for causing the barometric damper 229 to be held in substantially closed position. As a result the smoking of the fire is minimized and whatever smoke is emitted from the fire is prevented from entering the furnace room. After a period of time in which the volatile matter in the green coal in the retort is burned off the bimetal element 219 again assumes its cold position in which it causes closing of the air damper 226. The bimetal element in disengaging contact 220 deenergizes solenoids 230 and 231, causing them to assume the positions shown in which the barometric damper is held in wide open position. Thus after the stoker is stopped the air damper is held open and the barometric damper moved to closed position, the dampers being held in these positions for a period of time, the dampers then being caused to assume positions providing for minimum burning of the fire during the "off" or stand-by period.

While the present invention is especially suitable for stoker fired installations, its utility is not limited to installations of this type and certain features of the invention have utility in other types of systems, such as oil fired installations or even hand fired installations in which automatic

draft control is provided. While the use of the complete control systems shown and described is desirable, certain sub-combinations of control apparatus have utility apart from the complete combination. Also it will be apparent that many changes may be made without departing from the scope of the present invention. For this reason it is desired to be limited only by the scope of the appended claims.

What is claimed is:

1. In a control system for a furnace having combustion producing means and a flue, the combination of, control means influenced by the demand for heat from the furnace for selectively placing the combustion producing means into and out of operation, damper control means including damper means associated with the flue, said damper control means including means actuated upon placing of the combustion producing means into operation for causing movement of the damper means from a position of minimum draft to an intermediate position providing sufficient draft for satisfactory operation of the combustion producing means, means operative as an incident to the placing of the combustion producing means out of operation for causing movement of said damper means to a position providing maximum draft, and means for causing movement of said damper means to a position providing minimum draft after a substantial period of time.

2. In a control system for a furnace having combustion producing means and a flue, the combination of, control means influenced by the demand for heat from the furnace for selectively placing the combustion producing means into and out of operation, damper control means including damper means associated with the flue, said damper control means including means actuated as an incident to the placing of the combustion producing means into operation for causing movement of the damper means from a position of minimum draft to a position of maximum draft and for thereafter causing movement of said damper means to and stopping it at an intermediate position providing satisfactory draft for normal operation of the combustion producing means, and means operative upon placing of the combustion producing means out of operation for causing said damper means to remain in position for providing a substantial draft for a substantial period of time and for then causing the damper means to assume a position of minimum draft.

3. In a control system for a furnace having combustion producing means and a flue, the combination of, control means influenced by the demand for heat from the furnace for selectively placing the combustion producing means into and out of operation, damper control means including damper means associated with the flue, said damper control means including means actuated as an incident to the placing of the combustion producing means into operation for causing movement of the damper means from a position of minimum draft to a position of maximum draft and for thereafter causing movement of said damper means to an intermediate position providing satisfactory draft for normal operation of the combustion producing means, means operative as an incident to the placing of the combustion producing means out of operation for causing movement of said damper means to a position providing maximum draft, and means for

causing movement of said damper means to a position providing minimum draft after a substantial period of time.

4. In a control system for a furnace having combustion producing means and a flue, the combination of, control means influenced by the demand for heat from the furnace for selectively placing the combustion means into or out of operation, damper means associated with the flue for controlling the draft, means actuated as an incident to the combustion means being placed out of operation for causing movement of the damper means to a position providing increased draft and for maintaining it in such position, and means actuated a substantial period of time thereafter for causing movement of the damper means to a position of reduced draft.

5. In a control system for a furnace having combustion producing means and a flue, the combination of, control means influenced by the demand for heat from the furnace for selectively placing the combustion producing means into and out of operation, pressure responsive damper control means including damper means associated with the flue arranged to maintain a predetermined draft in the furnace when the combustion producing means is in operation, means actuated as an incident to the combustion producing means being placed out of operation for causing movement of the damper means to a position maintaining maximum draft, and means operative a substantial period of time after the combustion producing means is placed out of operation for causing movement of the damper means from said position of maximum draft.

6. In a control system for a furnace having combustion producing means and a flue, the combination of, control means influenced by the demand for heat from the furnace for selectively placing the combustion producing means into or out of operation, pressure responsive damper control means including damper means associated with the flue arranged to maintain a predetermined draft in the furnace when the combustion producing means is in operation, said damper control means including means actuated as an incident to the placing of the combustion producing means into operation for causing movement of the damper means from a position of minimum draft to a position of maximum draft and for thereafter causing movement of the damper means to a position providing said predetermined draft, and means actuated upon placing of the combustion producing means out of operation for causing said damper means to maintain at least said predetermined draft for a substantial period of time and for then causing said damper means to assume a position of minimum draft.

7. In a control system for a furnace having combustion producing means and a flue, the combination of, control means influenced by the demand for heat from the furnace for selectively placing the combustion producing means into or out of operation, pressure responsive damper control means including damper means associated with the flue arranged to maintain a predetermined draft in the furnace when the combustion producing means is in operation, said damper control means including means actuated as an incident to the placing of the combustion producing means into operation for causing movement of the damper means from a position of minimum draft to a position of maximum draft and for thereafter causing movement of the damper means to a position providing said predetermined

draft, means actuated as an incident to the placing of the combustion producing means out of operation for causing movement of the damper means to a position maintaining a maximum draft, and means operative a substantial period of time after the combustion producing means is placed out of operation for causing movement of the damper means to a position providing a minimum draft while the combustion producing means is out of operation.

8. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker for causing movement of said dampers from positions providing a minimum air supply to the fire and a minimum draft to positions providing a substantial supply of air to the fire and a substantial draft for withdrawing products of combustion, and means operative upon placing of the stoker out of operation for maintaining said dampers in positions for permitting air flow to the fire and providing substantial draft for a substantial period of time to minimize smoking, said last mentioned means causing said dampers to return to positions providing minimum air supply and minimum draft after said period of time.

9. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker for causing movement of said dampers from positions providing a minimum air supply to the fire and minimum draft to positions providing a substantial supply of air to the fire and a substantial draft for withdrawing products of combustion, means operative upon placing of the stoker out of operation for maintaining said air control damper in position to permit flow of air to the fire, means operative as an incident to such placing of the stoker out of operation for causing movement of said draft damper to a position of maximum draft for a substantial period of time to minimize smoking, and means for causing said dampers to return to positions providing minimum air supply and minimum draft after said period of time.

10. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker for causing movement of said dampers from positions providing a minimum air supply to the fire and minimum draft to positions providing a substantial supply of air to the fire and a substantial draft for withdrawing products of combustion, means operative upon placing of the stoker out of operation for maintaining said dampers in positions for permitting air flow to the fire and providing substantial draft for a substantial period of time to minimize smoking, said last mentioned means including a control device common to both of said dampers and actuated after said period of time for causing said dampers to return to positions

providing minimum air supply and minimum draft.

11. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker for causing movement of said dampers from positions providing a minimum air supply to the fire and minimum draft to positions providing a substantial supply of air to the fire and a substantial draft for withdrawing products of combustion, means operative upon placing of the stoker out of operation for maintaining said air control damper in position to permit flow of air to the fire, means operative as an incident to placing of the stoker out of operation for causing movement of said draft damper to a position of maximum draft to minimize smoking, and means including a control device common to both of said dampers and actuated after a substantial period of time following the placing of the stoker out of operation for causing said dampers to return to positions providing minimum air supply and minimum draft.

12. In a control system for a furnace having combustion producing means and a flue, the combination of, a combustion air pressure controlled air damper associated with the combustion producing means for maintaining a controlled supply of air for combustion, a draft controlled draft damper associated with the flue for controlling the draft for the furnace, and interlocking control means for said dampers and the combustion producing means for placing said combustion producing means out of operation and causing said dampers to assume positions of minimum air supply and draft, and for placing the combustion producing means in operation and rendering said dampers operative to maintain said controlled supply of air and said controlled draft.

13. In a control system for a stoker fired furnace having a flue, the combination of, control means influenced by the demand for heat from the furnace for selectively placing the stoker into and out of operation, an air control damper associated with the stoker, a draft control damper associated with the flue, first motor means for controlling the air damper, second motor means for controlling the draft damper, means operative upon placing of the stoker into operation for causing the second motor means to move the draft damper from a position of minimum draft to a position of maximum draft and for thereafter moving said draft damper to an intermediate position, means operative upon placing of the stoker out of operation to cause said first motor means to control the air supply damper in a manner to maintain a supply of air to the stoker and to cause the second motor means to move the draft damper from an intermediate position to a position of maximum draft, said last mentioned means including a single control device actuated after a substantial period of time following placing of the stoker out of operation, said single control device controlling both of said motor means and operative when actuated to cause said motor means to return the dampers to positions of minimum air supply and draft.

14. In a control system for a stoker fired furnace having a flue, the combination of, damper means associated with the flue for controlling the furnace draft, motor means for positioning said

damper means, a pressure actuated control device influenced by the products of combustion and adapted to control said motor means, means responsive to the demand for heat from the stoker for placing the same into and out of operation, means actuated upon the stoker being placed into operation for placing said control device in control of said motor means, said last recited means being actuated upon the stoker being placed out of operation for causing the motor means to operate the damper means to a position of minimum draft.

15. In a control system for a stoker fired furnace having a flue, the combination of, damper means associated with the flue for controlling the furnace draft, motor means for positioning said damper means, a pressure actuated control device influenced by the products of combustion and adapted to control said motor means, means responsive to the demand for heat from the stoker for placing the same into and out of operation, means actuated upon the stoker being placed into operation for placing said control device in control of said motor means and actuated upon the stoker being placed out of operation for causing the motor means to operate the damper means to a position of maximum draft to thereby minimize smoking, and timing means in control of said motor means and operative at the expiration of a timed period after the stoker is placed out of operation for causing the motor means to operate the damper means to a position of minimum draft.

16. In a control system for a stoker fired furnace having a flue, the combination of, damper means associated with the flue for controlling the furnace draft, motor means for positioning said damper means, a pressure actuated control device influenced by the products of combustion and adapted to control said motor means, means responsive to the demand for heat from the stoker for placing the same into and out of operation, means actuated upon the stoker being placed into operation for placing said control device in control of said motor means, and actuated upon the stoker being placed out of operation for causing the motor means to operate the damper means to a position of maximum draft to thereby minimize smoking, and means including a thermostatic device which changes in temperature as an incident to the stoker being placed out of operation for controlling said motor means, said thermostatic device causing the motor means to operate the damper means from said position of maximum draft to a position of minimum draft.

17. In a control system for a furnace having combustion producing means and a flue, the combination of, control means influenced by the demand for heat from the furnace for placing the combustion producing means into and out of operation, damper means associated with the flue, thermostatic means influenced by the temperature of the products of combustion and tending to cause said damper means to assume a position of minimum draft when said thermostatic means is relatively cold, whereby the draft through the furnace is maintained at a minimum when the combustion producing means is out of operation, electromagnetic means associated with

said damper means and operative to cause movement of the damper means from the position of minimum draft to a position of maximum draft upon placing of the combustion producing means into operation, and means controlled by said thermostatic means for causing movement of said damper means to an intermediate position when the thermostatic means becomes relatively hot.

18. In a control system for a furnace having combustion producing means and a flue, the combination of, control means influenced by the demand for heat from the furnace for placing the combustion producing means into and out of operation, damper means associated with the flue, thermostatic means influenced by the temperature of the products of combustion and tending to cause said damper means to assume a position of minimum draft when said thermostatic means is relatively cold, whereby the draft through the furnace is maintained at a minimum when the combustion producing means is out of operation, electromagnetic means associated with said damper means and operative upon placing of the combustion producing means out of operation to cause movement of the damper means to a position of maximum draft, and means controlled by said thermostatic means for causing movement of the damper means from said position of maximum draft to a position of minimum draft when the thermostatic means becomes relatively cool.

19. In a control system for a furnace having combustion producing means and a flue, the combination of, control means influenced by the demand for heat from the furnace for placing the combustion producing means into and out of operation, damper means associated with the flue, damper control means including an electro-magnet and a slow-acting device for positioning said damper means, said damper control means being controlled by said first mentioned control means and acting upon placing of the combustion producing means out of operation to cause movement of the damper means from an intermediate position to a position of maximum draft, said slow acting means a period of time thereafter causing movement of said damper means from said position of maximum draft.

20. In a control system for a stoker fired furnace having a flue, the combination of, control means influenced by the demand for heat from the furnace for selectively placing the stoker into and out of operation, and air control damper associated with the stoker, a draft control damper associated with the flue, and thermostatic means influenced by the temperature of the products of combustion for controlling both of said damper means, said thermostatic means when relatively cold tending to position said dampers for providing a minimum air supply and a minimum draft, and when relatively hot tending to cause said damper means to provide a substantial air supply and a substantial draft.

21. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker to cause relatively quick movement of the draft control damper from a position of minimum draft to a position of maximum draft and a substantial period of time thereafter to cause movement of the air control damper from a position of minimum air supply to

a position of substantial air supply, and means for causing said dampers to return to their positions of minimum air supply and minimum draft after the stoker is placed out of operation.

22. In a control system for a stoker fired furnace having a flue, the combination of, control means influenced by the demand for heat from the furnace for selectively placing the stoker into and out of operation, an air control damper associated with the stoker, a draft control damper associated with the flue, a slow acting device for controlling said air control damper, said device being rendered effective substantially when the stoker is placed into operation and causing movement of the air control damper from a position of minimum air supply to a position of substantial air supply a substantial period of time after the stoker is placed into operation whereby the air to the stoker is delayed until a quantity of coal is delivered to the stoker retort, motor means for positioning said draft control damper, said motor means being controlled by said control means and serving to cause movement of the draft control damper from a position of minimum draft to a position of substantial draft upon call for heat by said control means.

23. In a control system for a stoker fired furnace having a flue, the combination of, control means influenced by the demand for heat from the furnace for selectively placing the stoker into and out of operation, an air control damper associated with the stoker, a draft control damper associated with the flue, means including a thermostatic element associated with said air control damper for causing movement of the same from a position of minimum air supply to a position of substantial air supply as said element changes in temperature in a predetermined direction, an electric heating element for influencing said thermostatic element, said heating element being arranged under the control of said control means in a manner to cause movement of the air control damper from the position of minimum air supply to a position of maximum supply after the stoker is placed into operation, an electro-magnet for positioning said draft control damper, and means for controlling said electro-magnet in a manner to cause the draft control damper to move from a position of minimum draft to a position of maximum draft upon call for heat by said control means.

24. In a control system for a stoker fired furnace having a flue, the combination of, control means influenced by the demand for heat from the furnace for selectively placing the stoker into and out of operation, an air control damper associated with the stoker, a draft control damper associated with the flue, means including a slow acting timing device for actuating said air control damper, said timing device being rendered effective substantially when the stoker is placed into operation and causing movement of the air control damper from a position of minimum air supply to a position of substantial air supply a period of time after the stoker is placed into operation, motor means for positioning said draft control damper, and switching means actuated by said timing device for controlling said motor means.

25. In a control system for a stoker fired furnace having a flue, the combination of, control means influenced by the demand for heat from the furnace for selectively placing the stoker into and out of operation, an air control damper associated with the stoker, a draft control damper

associated with the flue, means including a slow acting timing device for actuating said air control damper, said timing device being rendered effective substantially when the stoker is placed into operation and causing movement of the air control damper from a position of minimum air supply to a position of substantial air supply a period of time after the stoker is placed into operation, switching means actuated by said timing device, motor means comprising a pair of electro-magnets for actuating said draft control damper, one electro-magnet being effective to move the draft control damper to a position of maximum draft and the other of said electro-magnets being effective to move the draft control damper to a position of minimum draft, said electromagnets being controlled conjointly by said control means and said switching means.

26. In a control system for a stoker fired furnace having a flue, the combination of, control means influenced by the demand for heat from the furnace for selectively placing the stoker into and out of operation, an air control damper associated with the stoker, a draft control damper associated with the flue, means including a slow acting timing device for actuating said air control damper, said timing device causing movement of the air control damper from a position of minimum air supply to a position of substantial air supply a period of time after the stoker is placed into operation, means for causing movement of the draft control damper to a position of maximum draft upon stopping of the stoker, and control means actuated by said timing device for causing movement of said draft control damper away from said position of maximum draft a substantial period of time after stopping of the stoker.

27. In a control system for a stoker fired furnace having a flue, the combination of, control means influenced by the demand for heat from the furnace for selectively placing the stoker into and out of operation, an air control damper associated with the stoker, a draft control damper associated with the flue, means actuated upon starting of the stoker for causing movement of said dampers from positions providing a minimum air supply to the fire and minimum draft to positions providing a substantial supply of air to the fire and a substantial draft for withdrawing products of combustion, said last mentioned means including timing means for delaying movement of the air control damper in draft increasing direction upon starting of the stoker until a quantity of fuel is supplied to the stoker retort, and for delaying movement of the draft damper in draft decreasing direction for a period of time upon stopping of the stoker.

28. In a control system for a furnace having combustion producing means and a flue, the combination of, control means influenced by the demand for heat from the furnace for placing the combustion producing means into and out of operation, a barometric damper associated with the flue and adapted to maintain a constant draft, electric motor means adapted in a first position to hold said damper substantially closed and in a second position to release said damper for normal operation, means for causing said motor means to move to said first position upon starting of the combustion producing means, and means including a slow acting device for causing said motor means to move to its second position a period of time thereafter.

29. In a control system for a furnace having

combustion producing means and a flue, the combination of, control means influenced by the demand for heat from the furnace for placing the combustion producing means into and out of operation, a barometric damper associated with the flue and adapted to maintain a constant draft, electric motor means adapted in a first position to hold said damper substantially closed and in a second position to release said damper for normal operation, means for causing said motor means to move from said second position to said first position upon stopping of the stoker, and means including a slow acting device for causing said motor means to move from said first position toward its second position a period of time thereafter.

30. In a control system for a furnace having combustion producing means and a flue, the combination of, control means influenced by the demand for heat from the furnace for selectively

placing the combustion producing means into and out of operation, a damper in the flue, a reversible motor for positioning the damper, a device responsive to the draft in the furnace for controlling the reversible motor, means controlled by said control means for placing the reversible motor under the control of the draft responsive device when the combustion producing means is in operation and for causing the reversible motor to operate the damper to a minimum draft position when the combustion producing means is out of operation, means for causing the damper to move to wide open position upon call for heat by the control means before the combustion producing means is placed in operation, and means for causing the damper to move to wide open position before moving to said minimum draft position, when the combustion producing means is placed out of operation.
